CLAIM

The ornamental design for a casket handle, as shown and described.

DESCRIPTION

FIG. 1 is a perspective view of the casket handle showing my new invention

FIG. 2 is a left side view thereof, the right side view being a mirror image of the left side view;

FIG. 3 is a front view thereof, the rear view being a mirror image of the front view;

FIG. 4 is a top view thereof; and,

FIG. 5 is a bottom view thereof.

The broken line showing of a casket and handle hardware is included for the purpose of illustrating environment and forms no part of the claimed design.

1 Claim, 4 Drawing Sheets

FIG. 4
